ARMORED ELECTRICAL PLUG

Filed April 7, 1927

UNITED STATES PATENT OFFICE

WILLIAM HUPPERT, OF NEW YORK, N. Y.

ARMORED ELECTRICAL PLUG

Application filed April 7, 1927. Serial No. 181,644.

This invention relates to armored electrical devices.

Pursuant to my invention, the electrical device such as a plug comprises a shell formed of sections of suitable insulating material, having the required recesses or other suitable interior formation for receiving the desired electrical contacts or set of the same, and further comprising exteriorly disposed strips, plates or the like of metal or like rigid non-fragile material to thereby armor the insulation sections to protect the same from chipping, cracking or breakage, and also to relieve the insulating material from localized strains.

Pursuant to my invention, the exterior armor is preferably formed or disposed to anchor wholly or partly supplemental parts such as the cord protecting spring, or the electrical cord per se, or the like, thereby insuring permanency of position of such anchored parts and effecting relief of strain otherwise sustained by the insulation material or other delicate part of the electrical device.

In the more preferred forms of my invention, the armoring is in the form of substantially duplicate punched metal sections, usually two, which interfit one another, each section being provided with tongues or the like serving to resiliently retain the insulating sections in position relative to one another.

Further features and objects of the invention will be more fully understood from the following detail description and the accompanying drawing, in which

Fig. 1 is a vertical elevation of an electrical plug embodying one form of my invention; the view shows a portion broken away in vertical section to illustrate otherwise hidden parts;

Fig. 2 is a central section elevation on line 2—2 of Fig. 1;

Fig. 3 is an exploded inner face plan view of a two-section style of shell embodying my invention;

Fig. 4 is a detail sectional elevation on line 4—4 of Fig. 1; and

Fig. 5 is a side elevational view of Fig. 1, on a slightly reduced scale, and showing

the electrical cord and its cord protecting spring in distorted positions.

Referring to the drawing, the shell of insulation of the electrical device illustrated, namely a plug, comprises a half-shell section 10 and co-acting half-shell section 11. Such multiple insulating shell sections are preferably of duplicate molded parts, in this instance two, one form of such preferred construction being described more fully herein-after.

It will be understood that the inner face portions of such molded insulation parts are suitably recessed and tapped or otherwise formed to provide for the reception and retention of the electrical contact elements, screws or equivalent for securing electrical connection of the electrical leads, also to anchor any of the electrical elements and for such or other purposes as will be understood by those skilled in the art.

Exteriorly of such shell of insulation, I provide suitable armoring means and in the drawing I have illustrated the oppositely disposed plates 12, 13 of iron, steel, or aluminum, either cast or shaped, such material being either inherently non-corrosive or rendered non-corrosive by plating, painting, dipping or the like. Such protecting plates 12, 13, 80 preferably extend from the forward end face 14 of the insulating material, substantially wholly about the opposite lateral faces and also to and about the rearward end face thereof.

As appears more fully hereinafter, such armoring means 12, 13 affords anchoring means for the cord protecting spring 15 or equivalent element.

To locate such armoring means 12, 13 on the insulation shell, 10, 11 I provide openings in the respective armoring sections 12, 13 registering with the openings in the insulation for the reception of the required retaining screws, bolts, rivets, enlarged eyelets or the like. Preferably, I employ screws as such retaining means and form the face of certain of such openings of the armoring means with a threading for retaining such screws. In Fig. 2 I have shown such preferred form,

namely the openings 16, 17 in the respective recessed portions 18, 19 of the plate 13, and the flanged recesses 20, 21 in the recessed portions 22, 23 of the co-acting plate 12, said flanges 20, 21 being provided with threading corresponding to the threading 24, 25 of the screws 26, 27. The extent of depression of the recesses 16, 17 should be sufficient to countersink the heads of the screws 26, 27.

10 It will be noted that the openings 28, 29 in the respective insulation sections 10, 11 for receiving the upper bolt 26 are disposed in spaced relation from the respective recesses designated generally 30 on the inner faces of such sections for receiving the electrical elements designated generally 31, and thereby precluding the leakage or arcing of current from such electrical elements 31 to the screw 26 or equivalent. Likewise, the openings 32, 20 33 in the respective insulation sections 10, 11 are similarly located for the reception of the screw 27 or equivalent.

As above indicated, my armoring means preferably further comprises a rearwardly extending portion for anchoring the cord protecting spring 15 or equivalent. As one form of such construction, I have cast or otherwise formed the respective armoring plates 10, 11 with an extension such as the 25 stepped cylindrical extensions 34, 35 of graduated reduced diameter. In this instance of two-sectional type of my armoring means, the stepped cylindrical flanges 34, 35, shown as two in number, are each of semi-cylindrical 30 shape and interconnected by an intermediate flange portion 36. The number of such cylindrical extensions may be as preferred.

The inner end 37 of the cord protecting spring 15 is readily assembled with such two-40 flange extension 34, 35, at the time of assembling the electrical plug, and such stepped relationship of the flanges 34, 35 affording a simple and highly effective anchoring of such spring end 37 upon the mere assembling of 45 the electrical plug parts and tightening-up the retaining screws 26, 27, and equivalent. The outer end 38 of the cord protecting spring 15 may be provided with a recessed thimble 38 of insulation, thereby attaining minimum 50 frictional wear of the outer end of the spring on the cord 39 passing therethrough.

It will be understood that the ends of the leads 40, 41 are opened up and the insulation stripped to expose the enclosed electrical 55 wires for connection with the respective screws 42, 43 of the electrical elements 31.

From the above description of my invention, it will be perceived that my armoring means is assembled to receive and withstand the strains and compressions arising upon tightening-up the screws or equivalent. Such strains, while somewhat localized in the metal armor at the areas of engagement of the threaded and headed ends of such screws or equivalent, are however distributed over the

body portions of the armoring plates, and thus protect the delicate insulation shell parts. The metal armor also readily withstands blows and protects the insulation from being chipped or cracked.

70 In the form of my armoring means as illustrated in the drawing, additional strain relief is furnished by my armoring means by the provision of the flanged or stepped extensions for receiving and retaining the cord 75 protecting spring. In Fig. 5, I have illustrated a position of the electrical cord 39, its protecting spring 15 assumed recurrently as when the plug 12, 13 is used with an electrical heating iron, soldering iron and the like.

80 As is indicated in Fig. 4, my armoring means 12, 13 extends preferably also at the lateral edges of the electrical plug 10, 11, such lateral extensions designated 12a, 13a being preferably overlapping as is indicated at 44. 85 If such ends 12a, 13a, do not overlap, it is desirable to locate the abutting edges of the same out of alignment with the plane of engagement of the inner faces of the insulation sections 10, 11, for precluding moisture or 90 other foreign substances into the electrical parts, and for preventing the insertion of a tool such as a screw driver, pen knife and the like therebetween.

95 My insulation sections are preferably of interlocking type and duplicate molded formation. As is indicated in Fig. 3, one form of interlocking embodies the elevated ridge 45 at the upper left-hand portion of the insulation section 11 and closely thereto of the depressed ridge section 46. At the upper right-hand portion of the section 11, see Fig. 3, I provide a depressed ridge portion 47, the depression of which corresponds to the extent of elevation of the elevated portion 45, to thereby receive the corresponding elevated portion 45a, of the insulation section 10 appearing at the right-hand in Fig. 3. Adjacent to the depressed ridge portion 47 I also provide the elevated ridge portion 48 having an elevation corresponding to the extent of depression of the depressed ridge portion 46, to thereby receive the corresponding depressed portion 46a of the insulation section 10, shown at the right in Fig. 3. The depressed ridge at the upper right-hand portion of the insulation section 10 is marked 47a and the adjacent elevated ridge portion is marked 48a, which respectively coact with the left-hand elevated ridge 45 and depressed ridge 46. Accordingly, upon assembly of 100 the coacting insulation sections 10, 11, their juxtaposed faces abut one another, accurately thus and readily aligning the insulation sections 10, 11 with one another, and retaining the same after securement of the retaining screws or equivalent.

105 110 115 120 125 130 The armoring sections 12, 13, are preferably of duplicate form by original punching operation, the opposite lateral outwardly ex-

tending edge portions 44, 44 being formed by secondary punching operation, also, preferably, each armoring section 12, 13, is provided with a tongue 50, see Figs. 1 and 2, each of which is formed from the body portion of its section by suitable U-shaped slot and bent inwardly, thereby serving to resiliently press the insulating sections 10, 11, toward one another upon assembling the armoring sections 12, 13, by their retaining screws 16, 17.

It will be observed that by my armoring means serving to retain the protecting spring 15 of the cord 39, the usual grooves formed at the upper ends of the insulating sections 10, 11, is obviated, thereby relieving the relatively delicate insulation of strains arising in the use of the plug, and particularly of strains directed at an angle to the strains of compression effected by the usual screws for retaining the insulating sections in position relative to one another.

As indicated hereinabove, my armoring means forms an envelope substantially completely surrounding the insulation, thereby protecting the insulation from injury by contact with other objects, or when dropped or the like. As appears from my invention, my armoring means may be made of metal, or facilitating the formation of the armoring sections, cheapness of cost and readability of finish or ornamentation, and when assembled relative to the insulating sections is protected from the "live" electrical parts by the insulating sections.

Whereas I have described my invention by reference to specific forms thereof, it will be understood that many changes and modifications may be made without departing from the spirit of the invention.

I claim:

1. In an electrical plug or like attachment device, the combination of a set of sections of insulation material, a set of elements formed of metal disposed exteriorly of said set of insulation sections, said metal sections being provided with projecting portions extending toward said insulation sections respectively and means for connecting said metal sections to one another and therewith disposing said projecting portions in resilient pressure against said insulation sections to retain said insulation sections in position.

2. In an electrical plug or like attachment device, the combination of a set of sections of insulation material, said insulation sections being provided with registering openings, a set of elements formed of metal disposed exteriorly of said set of insulation sections, said metal sections being provided with openings registering with one another and with said registering openings, said metal sections being provided with projecting portions extending toward said insulation sections re-

spectively and elements disposed in said registering openings for securing said metal sections in position relative to one another and to dispose said projecting portions in resilient engagement under pressure against said insulation sections. 70

3. In an electrical plug or like attachment device, the combination of a set of sections of insulation material, a set of elements formed of metal disposed exteriorly of said set of insulation sections, said metal sections being provided with projecting portions extending toward said insulation sections respectively and adjustable means for connecting said metal sections to one another and therewith disposing said projecting portions in resilient pressure against said insulation sections to retain said insulation sections in position. 75

4. In an electrical plug or like attachment device, the combination of insulation material provided with cavities for the reception of electrical terminals, said cavities extending jointly to one face of said plug for the reception of conductors leading to said terminals, a set of elements formed of metal disposed exteriorly of said insulation, said metal elements substantially completely embracing said insulation except at said one face, and means for connecting said metal sections and said insulation to one another, said metal sections projecting beyond said insulation at said one face, said projecting portions being bent toward one another to form an opening in said metal casing of a predetermined diameter when said metal sections are connected to one another, coil spring means for embracing said conductors at said one face, said coil spring means having a diameter materially less than said pre-determined diameter of the opening in said metal casing. 85

5. In an electrical plug or like attachment device, the combination of insulation material provided with cavities for the reception of electrical terminals, said cavities extending jointly to one face of said plug for the reception of conductors leading to said terminals, a set of elements formed of metal disposed exteriorly of said insulation, said metal elements substantially completely embracing said insulation except at said one face, and means for connecting said metal sections and said insulation to one another, said metal sections projecting beyond said insulation at said one face, said projecting portions being bent toward one another to form an opening in said metal casing of a pre-determined diameter when said metal sections are connected to one another, coil spring means for embracing said conductors at said one face, said coil spring means having a diameter materially less than said pre-determined diameter of the opening in said metal casing, said cavities extending to a certain face other than said one face, said insulation at said certain 105

face being recessed, said metal sections having projections at said certain face to extend within said recesses.

6. In an electrical plug or like attachment device, the combination of insulation material provided with cavities for the reception of electrical terminals, a set of interfitting elements formed of metal exteriorly of said insulation, said metal elements having abutting edges at certain side faces of said insulation, said abutting edges being offset in a plurality of directions with interfitting cut-away and tongue portions of the respective sections, and means for connecting said metal sections and said insulation to one another.

In testimony whereof I have signed this specification this 15th day of December 1926.

WILLIAM HUPPERT.
